CONVERTIBLE COLANDER AND MAT

Rachel E. Wille, Rte. 3, Box 204, Udina-Elgin, Ill.

Filed Oct. 1, 1959, Ser. No. 57,744

Term of patent 14 years

(Cl. D44—1)

Fig. 1 is a perspective view of a colander embodying my new design;

Fig. 2 is a bottom plan view thereof; and

Fig. 3 is a plan view thereof in unfolded position, for use as a mat.

I claim:

The ornamental design for a convertible colander and mat, substantially as shown.
